AIRSHIP

Alex A. Rommel, Fresno, Calif.

Application January 6, 1958, Serial No. 49,148

Term of patent 14 years

(Cl. D71—1)

FIG. 1.

FIG. 2.

Fig. 1 is a top plan view of an airship showing my new design.

Fig. 2 is a side elevation of the airship. Each of the other sides of the airship is of the same appearance as the side shown.

The dominant features of the design reside in the portions shown in full lines.

I claim:

The ornamental design for an airship, as shown and described.
